UNITED STATES PATENT OFFICE.

EDWARD H. HARGRAVE, OF CINCINNATI, OHIO, ASSIGNOR TO THE
CINCINNATI FOLDING BASKET COMPANY, OF OHIO.

BASKET.

SPECIFICATION forming part of Letters Patent No. 592,778, dated November 2, 1897.

Application filed May 4, 1896. Serial No. 590,105. (No model.)

To all whom it may concern:

Be it known that I, EDWARD H. HARGRAVE, a citizen of the United States, residing at Cincinnati, Ohio, have invented new and useful
5 Improvements in Baskets, of which the following is a specification.

My invention relates to baskets, its object being to provide a cheap and serviceable "knockdown" basket for ordinary use adapted to be packed into a small space for transportation and storage.

To this end the invention consists in a basket embodying a collapsible body and a pivoted "bail," the side arms of which are extended into struts to engage the bottom and expand the body, in combination with automatic locking devices to retain the bail and rim of the basket in proper engagement when the basket is open and adapted to be readily disengaged and permit the bail to be oscillated into the plane of the rim and inclosed within the same.

My improved basket is illustrated in the accompanying drawings, in which is shown, in—
25 Figure 1, a general perspective view of the basket open and expanded for use; Fig. 2, a view of the same collapsed ready for package or transportation. Figs. 3 and 4 are detail perspective views of the two clips constituting the locking device in connection with the pivot. Fig. 5 is a vertical cross-section of the basket, showing construction of the locking device and the relation of the bail-struts and bottom.

35 Referring now to the drawings, the basket-body A consists of a continuous rim a' and bottom a^2 , united by a web of textile material a^3 . The bail B is pivoted to the arm a' at each side by pivots p , and B has its arms extended into struts b , which when the basket is expanded, as shown in Figs. 1 and 5, engage against the bottom a^2 and hold the same downward against the residual elasticity of the web a^3 .

45 The fastening devices are located at the pivotal engagement of the bail B with the rim a' , the general function being that of a catch or bolt to automatically engage the bail B and rim when brought into the position indicated in Figs. 1 and 5 and so retain them until released.

The preferable construction shown herein is as follows: Clips or plates C' (shown in Fig. 3) are secured to the rim a' at opposite sides by the pivot p , which extends through 55 the plate c' and the rim a' and is riveted at the outside, as indicated in Fig. 5. The lower part of the plate is struck out to a half-circle concentric with the pivot and at the under side is provided with a recess t' . A corresponding plate or clip C² is provided for the bail B, having a tongue t' , turned outward at the lower end, adapted to engage the recess t , Fig. 4, and vertically-elongated slot O at the center. This plate is turned backward at 60 each side and fitted into corresponding recesses in the edges of the bail, to which it is secured, preferably, by a couple of pins or rivets x . When the bail B is in place, the pivot p extends through the slot O and a 65 corresponding aperture in the bail and is held by an enlarged head p' at the inner side of the bail B. When the bail B is thus fastened to the rim, it may occupy two positions in relation thereto, as indicated in Figs. 1 and 2. In the first of these, in which the side arms of the bail are perpendicular to the rim, the ends of the bail rest upon the bottom a^2 , and an upward pressure of the bottom, caused by the elastic tension of the covering material a^3 , holds the tongue t' in the recess t . In lieu of the elastic resiliency of the covering material, however, I may give the terminals b a slight inward bend at the bottom and avail myself of the resiliency of the terminals 85 themselves to produce the same result—namely, of holding the tongues t' in its recess t , thus locking the bail in perpendicular relations with the rim a' and holding the body of the basket distended. To disengage the 90 lock thus produced, it is only necessary to depress the bail in relation to the rim sufficiently to enable the tongue t' to clear the recess t , when the bail may be oscillated into the position indicated in Fig. 2, lying within the 95 rim a' . The bottom a^2 may then be brought up to the same plane, being enough to fit within the rim and between the terminals b , by the folding of the cover a^3 . When the basket is suspended by the bail B, the tongue t' is 100 held in the recess t and then securely locked, the tongue t' , together with the pivot, being

the elements by which the weight is sustained. The bottom of the basket is in this construction left entirely free of any fastenings or other obstruction.

5 I claim as my invention and desire to secure by Letters Patent of the United States—

1. In a knockdown basket of the character indicated, the combination of a pivot plate or clip having a recess at one edge attached to the rim, and a corresponding pivot-plate having a tongue turned outward at one edge attached to the bail, substantially as and for the purpose specified.

10 2. A knockdown basket, embodying a body portion consisting of a rim and bottom con-

nected by a flexible cover, in combination with its terminals extended into struts to rest against the bottom and distend the body, said bail having a vertical movement upon the pivot and a locking-tongue upon or in relation to the bail, engaging a locking-recess upon or in relation to the rim by said vertical movement, substantially as set forth.

15 In testimony whereof I have hereunto set my hand in the presence of two subscribing witnesses.

EDWARD II. HARGRAVE.
